COOKING UNIT FRONT

William R. Tappan and Truman B. Clark, Mansfield, Ohio,
assignors to The Tappan Stove Company, Mansfield,
Ohio, a corporation of Ohio

Application May 19, 1954, Serial No. 30,558

Term of patent 14 years

(Cl. D81—4)

The figure is a front perspective view of a cooking unit front showing our new design.

The other side of the front not shown is like the side shown.

The intermediate panel has been shown only partly perforated, for convenience of illustration.

It is to be understood that the perforations cover the entire panel in the relation shown.

We claim:

The ornamental design for a cooking unit front, as shown and described.
